(74) *Attorney, Agent, or Firm* — Michael P. Dunnam;
Culhane Meadows PLLC(57) **CLAIM**

The ornamental design for a napkin having a utensil pocket as shown and described.

DESCRIPTION

FIG. 1 is a top view of a napkin having a utensil pocket, showing the new design.

FIG. 2 is a top view of a napkin having a utensil pocket, showing the new design with a corner folded up to expose a lower layer.

FIG. 3 is a top end perspective view of the napkin having a utensil pocket showing the opening of the utensil pocket.

FIG. 4 is a top view of the napkin having a utensil pocket showing utensils inserted in the opening of the utensil pocket.

(Continued)

FIG. 5 is a left side view of a napkin having a utensil pocket, showing the new design.

FIG. 6 is a right side view of a napkin having a utensil pocket, showing the new design; and,

FIG. 7 is a bottom end side view of a napkin having a utensil pocket, showing the new design.

The stippled lines depict glue inserted between the layers to form a pocket and form part of the claimed design.

The broken lines depict environmental subject matter only and form no part of the claimed design.

1 Claim, 4 Drawing Sheets
